Primary Examiner — Catherine S Posthauer(74) *Attorney, Agent, or Firm* — Kimberly-Clark Worldwide, Inc.(57) **CLAIM**

I claim the ornamental design for a lid with push-button, as shown and described herein.

DESCRIPTION

FIG. 1 is a front perspective view of our lid with push-button showing our new design;

FIG. 2 is a right side view thereof; and,

FIG. 3 is a top view thereof.

The shade lines in the Figures show contour and not surface ornamentation.

The dot-dash lines represent environmental subject matter and form no part of the claimed design.
